TUNING ARRANGEMENT IN RADIO RECEIVERS

Dermot Min Ambrose, London, England, assignor to Standard Telephone and Cables Limited, London, England, a British company.

Application May 28, 1943, Serial No. 488,837
In Great Britain June 5, 1942

5 Claims. (Cl. 250—40)

The present invention relates to improvements in tuning indicators for radio receiving sets and the like, and employs the special properties of thermally sensitive resistance devices known as Thermistors for increasing the sensitivity of the indications.

Thermistors have been in use for some years and are characterized by a temperature coefficient of resistance which may be either positive or negative and which is moreover many times the corresponding coefficient for a pure metal such as copper. This property renders thermistors particularly suitable for a variety of special applications in electric circuits.

Various different materials are available for the resistance element of a thermistor, these various materials having different properties in other respects; as one example, a resistance material having a high negative temperature coefficient of resistance comprises a mixture of manganese oxide and nickel oxide, with or without the addition of certain other metallic oxides, the mixture being suitably heat treated.

Thermistors have been employed in two different forms: (a) known as a Directly Heated Thermistor and comprising a resistance element of the thermally sensitive resistance material provided with suitable lead-out conductors or terminals, and (b) known as an Indirectly Heated Thermistor comprising the element (a) provided in addition with a heating coil electrically insulated from the element. A directly heated thermistor is primarily intended to be controlled by the current which flows through it and which varies the temperature and also the resistance accordingly. Such a thermistor will also be affected by the temperature of its surroundings and may therefore be used for thermostatic control and like purposes with or without direct heating by the current flowing through it. An indirectly heated thermistor is chiefly designed to be heated by a controlling current which flows through the heating coil and which will usually, but not necessarily, be different from the current which flows through the resistance element, but this type of thermistor may also be subjected to either or both of the types of control applicable to a directly heated thermistor.

More detailed information on the properties of thermistors will be found in an article by G. L. Pearson in the Bell Laboratories' Record, Dec. 1940, page 106.

In radio receiving sets, it is now common practice to supply some means of indicating when the set is accurately tuned to a desired transmitting

station. For this purpose cathode-ray tube indicators of various types have been used, and also gas discharge tubes and incandescent electric lamps have been employed where a cheaper arrangement is desired. By associating an indirectly heated thermistor with the circuit, the sensitivity of these cheaper arrangements may be increased.

According to the invention, therefore, there is provided a tuning indicating arrangement for a radio receiver provided with automatic volume control, comprising an indirectly heated thermistor having its heating coil connected in series with the plate circuit of a thermionic valve in the receiver, the plate current of which valve is varied by the operation of the volume control, the resistance element of the thermistor being connected in a local circuit with a tuning indicator and adapted to control the indicator in accordance with the changes in the tuning adjustment of the receiver.

The invention will be more clearly understood from the following detailed description with reference to the accompanying drawing in which:

25 Fig. 1 shows a schematic circuit diagram of one embodiment of the invention; and

Fig. 2 shows a modification of part of Fig. 1.

Referring to Fig. 1, the valve V is shown as an intermediate frequency amplifying valve in a radio receiver, for example. Incoming signals are applied to the control grid circuit from terminals 1 and 2 and after amplification are delivered to the next stage (not shown) through the output transformer OT and terminals 3 and 4. The transformer has its primary winding connected in series with the plate circuit of the valve and the primary and secondary windings are tuned by means of the condensers C₃ and C₄ respectively.

30 The cathode of the valve is suitably biased by means of the series resistance R₂ with the usual bypass condenser C₂ and a negative voltage derived from an automatic volume control arrangement (not shown) of any well-known type is applied through terminal 5 to an auxiliary grid of the valve V. A blocking condenser C₁ completes the circuit for alternating currents.

So far the circuit which has been described is conventional, and might be provided in a number of other well known ways.

In accordance with the invention, the positive terminal of the high tension supply for the plate of the valve V is connected from terminal 6 through the heating coil r of an indirectly heated thermistor T whose resistance element R is con-

nected in parallel with an incandescent electric lamp L which is lighted from a suitable constant voltage source S connected to the terminals 7 and 8, in series with a constant resistance R₁. The source S may supply either alternating or direct current, and might be the same as one of the power supplies for the valve V or other valves of the receiving set.

It will be first assumed that the thermistor has a negative temperature coefficient of resistance, so that it has a low resistance when the current through the heating coil r is large.

When the receiver is not tuned to a station, the incoming signals at terminals 1 and 2 will be of very low level, and the automatic volume control negative voltage at terminal 5 will be small. The plate current of the valve V will accordingly be large, the thermistor resistance R will be low, and the lamp L will accordingly be heavily shunted and will glow only faintly, if at all.

When the receiver is brought into tune the signal level increases, and the negative automatic volume control voltage also increases and reduces the amplification of the valve V and also the plate current. The thermistor cools and its resistance R increases, so that the lamp glows more brightly. Accurate tuning will be shown by a maximum brilliancy of the lamp, since the plate current will increase again as soon as the tuning point is passed.

If the lamp L is connected in series instead of in parallel with the resistance R of the thermistor T, it will be evident that the indication of accurate tuning will be given by minimum brilliancy of the lamp instead of maximum brilliancy, and this arrangement may be preferred.

It will be evident that a thermistor with a positive temperature coefficient of resistance may also be used. This will give minimum brightness when the circuit is properly tuned in the arrangement of Fig. 1, and maximum brightness in the alternative arrangement when the lamp L is in series with the resistance R.

Whichever of the four possible arrangements is employed, it will, of course, be necessary to choose the voltage of the source S, the resistances of the lamp L, and R₁, and the range of resistance change of the thermistor T, so that the largest variation of the brightness of the lamp is obtained corresponding to the known variations of the plate current of the valve V caused by action of the automatic volume control. This will not present any difficulty when the conditions are given, and the range of choice of the thermistor resistance is very wide.

The thermistor T may also be arranged to control a neon tube indicator in the manner shown in Fig. 2. This figure shows the modification of that part of Fig. 1 which is below and to the right-hand side of terminal A; everything above and to the left-hand side of A is the same.

N is a neon tube indicator or other like gas discharge device having a cathode 11 of relatively large area, a small control electrode 12, and a small anode 13. The cathode 11 is given a suitable small positive potential by connection to an adjustable contact on a resistance potentiometer P connected between the positive and negative high tension terminals 6 and 9, the negative terminal 9 being preferably connected to ground as shown. The anode 13 is connected to terminal 9 through a resistance R₅ and will acquire a positive potential.

The resistance element R of the thermistor T is connected with one terminal to 9 and the other

terminal to the positive high tension terminal 6 through a resistance R₃. This other terminal of the resistance R is also connected through a resistance R₄ to the control electrode 12 of the neon tube.

Assuming first of all that the thermistor has a negative temperature coefficient of resistance, the resistance R will be a maximum when the receiver is in tune, the plate current of the valve V in Fig. 1 being a minimum under this condition. This will raise the control electrode 12 of the neon tube N (Fig. 2) to a maximum positive potential, and will in turn cause the glow in the tube N to be of maximum brightness and to cover a maximum area on the cathode 11. When the receiver is untuned, the control electrode 12 will be at a low potential and there will be little or no glow.

A thermistor with a positive temperature coefficient of resistance will produce a substantially similar effect if R and R₃ are interchanged in Fig. 2. In this case the resistance R will be a minimum when the receiver is in tune so that it will cause the control electrode 12 to assume a maximum positive potential as before.

It will generally be preferable to operate the neon tube from the same high tension supply as the valve V as indicated in Figs. 1 and 2; but if preferred, a separate supply could be used, which would be connected to terminal 10, the connection B between terminals 6 and 10 being removed.

It is of course not essential to apply the invention to an intermediate frequency valve. Any other valve similarly controlled so that its plate current is varied in accordance with the signal level could be used instead.

By suitable choice of the resistance r of the heating coil of the thermistor T in Figs. 1 and 2, the sensitivity of the indicators can be made greater than if the thermistor were not used.

What is claimed is:

1. In a radio receiver having an amplifying valve including a plate circuit the plate current of which valve is varied by the level of signals entering said valve, a tuning indicating device comprising a thermistor having a thermally sensitive resistance element and a heating coil electrically insulated from said element, a series connection from said coil to said plate circuit, a local circuit connected to said resistance element and a tuning indicator in said local circuit connected to said resistance element, whereby said resistance element is adapted to control said indicator in accordance with the changes in the tuning adjustment of the radio receiver, and whereby no transfer of electrical energy between said plate circuit and said indicator takes place.

2. In a radio receiver having an amplifying valve including a plate circuit the plate current of which valve is varied by the level of signals reaching said valve, a tuning indicating device comprising a thermistor having a thermally sensitive resistance element and a heating coil electrically insulated from said element, a series connection from said coil to said plate circuit, a local circuit connected to said resistance element, an incandescent lamp in said local circuit connected to said resistance element and a source of electromotive force for supplying current to said lamp, whereby said resistance element controls said incandescent lamp in accordance with the changes in the tuning adjustment of the radio receiver, and whereby no transfer of electrical energy between said plate circuit and said indicator takes place.

3. In a radio receiver having an amplifying valve including a plate circuit the plate current of which valve is varied by signals entering said valve, a tuning indicating device comprising a thermistor having a thermally sensitive resistance element and a heating coil electrically insulated from said element, a series connection from said coil to said plate circuit, a local circuit, an incandescent lamp in said circuit connected in parallel with said resistance element, a source of electromotive force for supplying current to said lamp and a constant resistance connected in series with said source of electromotive force, whereby no transfer of electrical energy between said plate circuit and said indicator takes place.

4. In a radio receiver having an amplifying valve including a plate circuit the plate current of which valve is varied by signals entering said valve, a tuning indicating device comprising a thermistor having a thermally sensitive resistance element and a heating coil electrically insulated from said element, a series connection from said coil to said plate circuit, a local circuit connected to said resistance element, a gas-discharge tube in said local circuit connected to said resistance element and a source of electromotive

force for supplying current to said gas-discharge tube, whereby no transfer of electrical energy between said plate circuit and said indicator takes place.

5. In a radio receiver having an amplifying valve including a plate circuit the plate current of which valve is varied by signals reaching said valve, a tuning indicating device comprising a thermistor having a thermally sensitive resistance element and a heating coil electrically insulated from said element, a series connection from said coil to said plate circuit, a local circuit, a gas-discharge tube in said local circuit, said gas-discharge tube comprising a cathode, an anode and a control electrode, a source of constant voltage connected to supply said tube, a constant resistance across said source and to which said resistance element is connected in series, a connection from said control element to the junction point of said resistance element and said constant resistance, and a second constant resistance in series with said last named connection, whereby no transfer of electrical energy between said plate circuit and said indicator takes place.
